US00D776707S

(12) **United States Design Patent** (10) **Patent No.:** **US D776,707 S**
Jiang et al. (45) **Date of Patent:** **** Jan. 17, 2017**

(54) **DISPLAY SCREEN OR PORTION THEREOF WITH A GRAPHICAL USER INTERFACE**

(71) Applicant: **SHELL INTERNET (BEIJING) SECURITY TECHNOLOGY CO., LTD.**, Beijing (CN)

(72) Inventors: **Xiaoming Jiang**, Beijing (CN); **Jian Yan**, Beijing (CN); **Xiongfeng Yu**, Beijing (CN); **Ming Xu**, Beijing (CN)

(73) Assignee: **SHELL INTERNET (BEIJING) SECURITY TECHNOLOGY CO.**, Beijing (CN)

(**) Term: **14 Years**

(21) Appl. No.: **29/489,681**

(22) Filed: **May 1, 2014**

Related U.S. Application Data

(63) Continuation of application No. PCT/CN2014/074869, filed on Apr. 4, 2014.

(51) **LOC (10) Cl.** **14-04**

(52) **U.S. Cl.**

USPC **D14/488**

(57) **CLAIM**

The ornamental design for a display screen or portion thereof with a graphical user interface, as shown and described.

DESCRIPTION

FIG. 1 is a front view of a display screen or portion thereof with a graphical user interface; and, FIG. 2 is a front view of another embodiment of a display screen or portion thereof with a graphical user interface. The broken lines illustrate portions of the article and portions of the graphical user interface. None of the broken lines form part of the claimed design.

1 Claim, 2 Drawing Sheets
